ton is not being transported, and the cross bar 11 of the rectangular end members will engage against the end of the carton when the carton is transported.

In the form of the invention shown in Figs. 6, 7 and 8, the handle may be stamped or cut from a single sheet of material 25 such as metal, aluminum, plastic or the like, comprising an elongated body forming the handle 26 by folding the same on the fold line 27 and turning the same downwardly and inwardly until the respective ends engage each other as indicated at 28 (Fig. 7) to form a substantially rounded portion on the bottom of the handle to prevent injury to the hands and a substantially plane surface 29 for advertising as indicated at 30 (Fig. 6). Extending outwardly from the handle 26 are substantially triangular-shaped portions 31 and 32 bent downwardly slightly as indicated at 33 and 34 forming end portions 35 and 36 extending substantially vertically downwardly from the slightly inclined portions. The end portions 35 and 36 are provided with extensions 37-38 and 39-40, respectively, adapted to be folded as indicated by the dotted lines 41 and 42 to form hooks 43-44 and 45-46 on the respective ends of the device, the hooks being turned inwardly from the end portions 35 and 36 to engage in the openings of cartons or the like as in the form of the invention shown in Figs. 1 to 5 inclusive.

With this form of the invention the substantially triangular-shaped members emanating from the handle portion are also provided with advertising matter as indicated at 47 (Fig. 6).

The ends of the handle member in this form of the invention are also tensioned slightly inwardly and the hooks on one end may be inserted in the openings in the carton and then slight tension outwardly on the opposite ends will engage the hooks in the openings on the opposite ends of the cartons and retain the same therein. The inside of the substantially plane end portions 35 and 36 on the handle will engage against the sides of the ends of the carton to make a rigid structure for transporting the car-

ton is not being transported, and the cross bar 11 of the rectangular end members will engage against the end of the carton when the carton is transported.

I claim:

A detachable handle for cartons having laterally spaced openings in the ends thereof comprising, an elongated body member forming a hand hold, said body member being two wire portions twisted one around the other, end members on the ends of the body member, said end members being wire loops having downwardly inclined diverging portions terminating in depending laterally spaced substantially parallel portions having inturned lower ends forming hooks adapted to engage in the spaced openings in the ends of the carton, said inturned ends being connected by inverted U-shaped cross bars in the planes of the depending laterally spaced portions for engaging the ends of the carton, and brace members of sheet material substantially coextensive with and extending between the diverging portions and having edges turned therearound for retaining said diverging portions against relative lateral and bending movement.

GLEN G. SIMMONDS.
